DESIGN FOR A RING OR SIMILAR ARTICLE

**Fred Jaske, Alameda, and Carl M. Johnson,
San Francisco, Calif.**

Application August 17, 1936, Serial No. 64,438

Term of patent 3½ years

To all whom it may concern:

Be it known that we, Fred Jaske and Carl M. Johnson, citizens of the United States, residing, respectively, in Alameda, in the county of Alameda, State of California, and in the city and county of San Francisco, State of California, have invented a new, original, and ornamental Design for a Ring or Similar Article, of which the following is a specification, reference being had to the accompanying drawing, forming part thereof.

Fig. 1 is a fragmentary plan view of a ring showing our new design;

Fig. 2 is a side view of such a ring;

Fig. 3 is a sectional view taken on lines 3—3 of Fig. 1.

We claim:

The ornamental design for a ring or similar article, as shown.

**FRED JASKE,
CARL M. JOHNSON.**
